CARTON FOR PACKING BOXES IN UNITS OF FIVE

Colin A. Ross, Troy, N. Y., assignor to Behr-Manning Corporation, Troy, N. Y., a corporation of Massachusetts

Application October 9, 1950, Serial No. 189,212

2 Claims. (Cl. 229—27)

The present invention relates to a carton which is adapted for packing and shipping units of five boxes. Units of five boxes in one shipping carton have become of importance in the trade for the reason that it is desirable to maintain the decimal system in working out packages which the jobber and dealer can handle easily. For example, a unit of six or seven boxes within one carton would destroy uniformity which can be provided with the decimal system. Moreover, the unit of five is in most instances the most economical unit which the dealer and jobber can handle.

Although the problem of providing a carton which can carry a unit of five boxes does not sound difficult, it has been found heretofore that the use of stuffing such as bunches of corrugated paper, excelsior, shredded paper or the like when used in a rectangular or square carton of the usual type in order to take up the excess space is not only expensive and time consuming in the packing of the carton but also encounters difficulty because of the shifting of the packages during shipping and handling with occasional consequential damage to the same.

Further, in shipping units of five an attempt has been made to make use of an elongated rectangular carton which will carry the five inner boxes in a single line. This method has not met with any great degree of success in view of the difficulty of handling the carton during shipping because of its shape and the further difficulty of storing the carton upon arrival at its destination.

It is, therefore, a principal object of this invention to provide a carton of preferably the square type which will suitably contain units of five boxes without the necessity of using packing which is expensive and time consuming in the packing of the carton and which because of its shape does not encounter difficult shipping and storage problems.

A further object of the invention is to provide a carton capable of the above uses which is of rugged yet of simple construction and which may be manufactured at a minimum cost.

In the drawings which illustrate a preferred form of the invention:

Figure 1 is a perspective view of an assembled carton of this invention showing the top inner and outer flaps in their opened position;

Figure 2 is a perspective view similar to Figure 1 showing five packing units positioned within the carton;

Figure 3 is a perspective view similar to Figure 2 showing the top inner flaps folded inwardly in a closed position;

Figure 4 is a vertical cross-sectional view along the line 4—4 of Figure 3;

Figure 5 is a vertical cross-sectional view along the line 5—5 of Figure 4; and

Figure 6 is a plan view of a blank from which the carton of this invention is formed.

As shown in Figures 1 through 3 of the drawings, the carton of this invention comprises side and end walls and top and bottom closures; the top and bottom closures each including, when the carton is closed, a pair of opposed inner flaps carried by the side walls. Each inner flap has a portion intermediate its width foldable inwardly into the box on a line intermediate the length of its flap. These intermediate portions when folded inwardly define a well whose inner dimensions are substantially the same as one of the packing units to be positioned in the carton. The four remaining packing units are positioned in each corner of the carton so as to

2

retain the first packing unit with the aid of the well centrally in a fixed position within the carton.

The carton of Figures 1 through 3 of a heavy-type cardboard, single-faced corrugated board, double-faced corrugated board, or other similar material is constructed from a rectangular blank shown in its entirety as 10 in Figure 6 to which reference will be now had in order to describe the carton of this invention with more particularity.

10 The rectangular blank 10 is scored with two longitudinal score lines 11 and 12 extending in a parallel relation through the length thereof and dividing the width of the blank 10 into three portions. The blank 10 is further scored with transverse double score lines 13, 14 and 15 which divide the carton into side walls 16 and 18 and end walls 17 and 19. The carton is cut along the score lines 13, 14 and 15 to form slots 20 which extend from opposite edges of the blank up to their respective score lines 11 or 12. The slots 20 along with score lines 11 and 12 define inner bottom flaps 21, inner top flaps 22, outer bottom flaps 23 and outer top flaps 24. Inner bottom flaps 21 and inner top flaps 22 are additionally scored along lines 25 which may extend the width of their respective flaps for ease of scoring and are parallel to score lines 11 and 12, score lines 25 being positioned substantially intermediate their respective score lines 11 or 12 and the free edge of their respective flaps. Each of the inner bottom flaps 21 and the inner top flaps 22 are provided with two slots 26 which extend from the free edge of their flap up to and normal to its score line 25. The inner portions 27 defined by the slots 26 and score lines 25, as described hereinafter, are folded inwardly during the assembly of the carton at an angle normal to their respective inner flaps for the purpose of providing a retaining well for a centrally located box forming one of the five boxes to be packed in the carton formed from the blank 10.

The carton described above as being formed from the rectangular blank 10 may be either rectangular or square. 40 In the preferred form of the invention, as is illustrated in the drawings, the form of the assembled carton is substantially square. Further, the width of each of the flaps 21, 22, 23 and 24 is equally substantially to one-half the length of each of the equal length side and end walls 16, 17, 18 and 19. Such a width permits the free ends of opposed pairs of flaps to come into substantially abutting relationship upon closing the carton flaps. Furthermore, each of the widths of the intermediate portions 27 is equal substantially to one-half the width of its respective flaps in order that the free ends of the intermediate portions 27 of the inner top and bottom closing flaps on one end wall may come into substantially abutting relationship upon forming the well which retains one of the five packing units centrally within the carton. 50 Also in the preferred form of the invention wherein the five units packed in the carton are equal in size, the length of each of the intermediate portions 27 will be equal substantially to one-third the length of its respective inner flap.

60 Assembly of the carton from the blank 10 as shown in Figure 1 may be accomplished by folding the blank along the score lines 13, 14 and 15 to bring free edges 28 and 29 in abutting relationship, sealing these free edges together by the use of the usual adhesive tape or 65 other means employed for assembling cartons, folding the inner bottom flaps 21 inwardly at an angle substantially normal to their respective side walls, then folding the intermediate portions of the bottom flaps 21 inwardly into the box along the score lines 25, folding the outer bottom flaps in overlapping relationship with the inner bottom flaps, and sealing the abutting free ends 30 and 31 by an adhesive-type tape and reinforcing the bottom of the box, if desired, by stapling through the inner and outer bottom flaps. The carton is packed by placing the 70 five boxes in the carton in the position shown, one of the five boxes being placed centrally within the well formed by the intermediate portions 27 of the inner bottom flaps 21 as shown in Figure 2, folding the inner top flaps 22 inwardly into a closed position with the intermediate portions 27 in the position shown in Figure 75 3, closing the outer top flaps 24 in overlapping relation-

ship with the inner top flaps 22, and sealing with the use of an adhesive tape.

It is further within the scope of this invention, as is apparent, to position two or more packing units in each space occupied by one of the described five units and still maintain the desired decimal system count of units. The total volume of the two or more packing units when placed side by side or on top of each other would be equal to that volume occupied by one packing unit.

From the above description, it is seen that a carton has been provided which does not require the use of packing materials such as excelsior, shredded newspaper, etc., but which does permit the packing of boxes in units of five without the possibility of shifting in the carton during shipping. Also, it is apparent that the carton provided is of a rugged yet simple construction which may be manufactured at a minimum cost in a shape which does not cause difficulties in shipping and storing. Furthermore, the structure of the described carton of this invention permits the inspection of the contents of the carton or permits the carton to be used for display purposes if each of the five units are identical by merely breaking open the seal of the upper outer opposed flaps and thereby permitting inspection of the contents within the well. If desired, also, the well may be made of a size smaller or larger than that space occupied by one of the other packing units in order that a fifth unit may be carried which is of different size and shape than the other four units.

As a packing unit in the centrally located well, a hollow cardboard sleeve having a cross-section conforming to the space in the well and a height equal to that of the sides of the carton may be positioned in the well. The hollow sleeve may serve as a reservoir for loose items or accessory items related to the goods packed in the remaining four packing units. The flaps 27 at the top of the carton may be inserted adjacent to the sleeve as described hereinbefore or may be left unfolded and allowed to overlay the top of the carton along with the remainder of the flaps 22.

Other modifications and forms of the invention than that described will be apparent to those skilled in the art, the description and the drawings being, therefore, only illustrative of the invention and not limiting.

I claim:

1. A slotted blank for folding into a carton which comprises a rectangular blank of sheet material, two parallel scores on one face thereof which run parallel to the longest edges of said blank substantially equally spaced from one another and from the nearest longest edge, three parallel scores on the same face of said

5 blank which run parallel to the short edges thereof, said three scores being substantially equally spaced from one another and with the outside scores being substantially equally spaced from the nearest short edge, the sheet material along each of said three scores located between the long edges of the blank and the closest of said first two scores being cut out to form slots forming four flaps on each side of the blank attached to the central body of the blank along said two scores, scores in the first and 10 third of said flaps on each side of said blank along approximately the transverse median line thereof and two parallel spaced slots in each of said first and third flaps only on each side of said blank, which slots run normally in from the outer edge of their respective flap to meet said intermediate score in said flap and divide said outer edge into substantially three equal parts.

15 2. A carton for packing units in multiples of five to give a balanced package made by folding a rectangular blank into a carton which comprises four side walls of substantially the same length and top and bottom closures, each closure including when the carton is closed a pair of opposed straight end abutting outer flaps of substantially equal length carried by two opposite side walls, and a pair of opposed, straight end abutting inner flaps of substantially equal length carried by the other 20 pair of opposite side walls, each inner flap only having two parallel spaced slots therein which run normally from said straight edge of the flap dividing said edge into three equal parts and extending into said flap to substantially 25 the transverse median line thereof and defining an intermediate portion in the outer section of the flap, said intermediate portions of the inner flaps being folded inwardly normally of the plane of the inner flaps directly in a straight line into the interior of the carton with the opposed, inwardly folded intermediate portions of the 30 top and bottom closures being substantially in alignment defining an inner well in the carton.
